UNITED STATES PATENT OFFICE.

HAROLD ROBERT SUITER, OF RED LODGE, MONTANA.

FORM FOR MOLDS.

Application filed October 19, 1921. Serial No. 502,769.

To all whom it may concern:

Be it known that I, HAROLD R. SUITER, a citizen of the United States, and resident of Red Lodge, in the county of Carbon and State of Montana, have invented certain new and useful Improvements in Forms for Molds, of which the following is a specification.

This invention relates to forms especially adapted for use in building construction.

An important object of this invention is to provide a building form for concrete walls which may be readily placed in position and which may be easily and quickly moved and reset for the continuation of the wall and which will require a minimum of material.

A further object is to provide a concrete form wherein all of the parts may be recovered for subsequent use.

A further object is to provide a building form for walls which is of highly simplified construction, durable in use and cheap to manufacture.

Other objects and advantages of the invention will be apparent during the course of the following description.

In the accompanying drawings forming a part of this application and in which like numerals are employed to designate like parts throughout the same,

Figure 1 is a fragmentary side elevation of the improved mold or form in use.

Figure 2 is a vertical sectional view through the same.

Figure 3 is a fragmentary plan view illustrating the use of the mold.

Figure 4 is a plan view of a tie plate embodied in the invention, the release rods being extended through the tie plate.

Figure 5 is a perspective of a clip embodied in the invention.

Figure 6 is a perspective of another clip embodied in the invention.

Figure 7 is a perspective of another clip embodied in the invention.

Figure 8 is a perspective of a tool adapted for use in connection with the invention.

Figure 9 is a perspective of another tool embodied in the invention.

Figure 10 is an enlarged fragmentary perspective of the tool illustrated in Figure 9.

Figure 11 is a perspective of a releasing tool embodied in the invention, the same being used in connecting a single wall.

In the drawings, the numerals 10 designate a plurality of mold boards arranged in edge to edge relation to form spaced sides of the form and the mold boards 10 are connected by tie plates 11 extended between the boards and having round or circular openings 12 through which connecting rods 13 are extended, the said connecting rods 13 being rounded with the exception of the flat side 14 which forms a means whereby the mold boards 10 may be released or loosened from the wall.

Specifically the form is assembled as illustrated in Figures 1 and 2 wherein the tie plates 11 are shown as being extended between the opposed edges of the form boards 10 and having their terminal portions extended beyond the mold boards. When in this position the connecting rods 13 are extended through the apertures or openings 12 and the rounded sides of the rods are engaged with the sides of the openings 12 adjacent the boards 10 so that the boards will be moved inwardly to the limit of their movement. The wall may be composed of spaced sections as illustrated in Fig. 2 or it may be formed of a single thickness. With reference to Figure 3 it will be seen that the mold boards 10 are separated by spacing blocks 18 and are securely held in a set position thereby.

The several mold boards may be connected at their ends by clips illustrated in Figure 6 and generally designated by the numeral 20, the said clips being provided with downwardly directed flanges 21 which engage opposite sides of one of the intermediate boards and with upwardly directed flanges 22 which engage the ends of adjacent boards. The application of the clips is clearly illustrated in Figure 1 wherein the downwardly directed flanges 21 are shown in engagement with one of the intermediate boards while the upwardly directed flanges 22 are in engagement with the end portions of adjacent boards. That is to say, the pairs of upwardly directed flanges 22 which are arranged in spaced relation engage the ends of aligned boards so as to prevent the form from bulging at any point.

The adjacent ends of the upper form board may be connected by a clip generally designated by the numeral 25 as clearly illustrated in Figures 1 and 5. The clip 25 is of U-shaped formation and the spaced sides of the

same extend over the adjacent ends of the boards to prevent the same from bulging.

When forming a right angle mold as illustrated in Figures 1 and 3 the ends of the sections 10 are provided with cleats 30 which extend beyond the edges of the boards and engage adjacent boards so as to hold the same in position. The cleats 30 may be connected to the board and form a means for holding the several sections together. The cleats which are secured to the extended boards flatly contact with the sides of the boards which terminate at the ends of the wall or more particularly at the corner of the same and thereby prevent the boards from moving outwardly.

Additional cleats 31 may be secured to the edges of the board and are provided with laterally projecting terminal portions 33 flatly contacting with the sides of the boards to hold the same in position.

In assembling the form the frame 40 of openings such as doors or windows may be arranged in place without interfering with the setting up of the form and it will be seen that the sides and ends of the frame 40 provide abutments for the cement 41.

When the cement has been poured into the mold, the lower mold board 10 may be removed and placed upon what was originally the upper mold board. The connecting rods 13 are now raised so as to lie on the outer sides of the boards 10 and additional tie plates 11 are arranged on the upper edges of the several mold boards.

It will be understood that when it is desired to remove any of the form boards 10 it is merely necessary to turn each connecting rod so that the flat side of the same is arranged inwardly thereby releasing the form board.

If desired the tie plates 11 which are tapered may be allowed to remain in the wall and the projecting ends of the same severed. On the other hand if desired, the tie plates which are tapered may be driven out of the wall. In that case the tie plates are dipped in melted paraffin before being arranged in place so that the coating forms a means whereby the tie plates may be readily removed. The tool illustrated in Figure 11 and generally designated by the numeral 54 is formed at its ends with openings 51 of a size to snugly receive the connecting rods 13 so that the connecting rods may be turned when desired either for releasing or locking the boards 10.

The tool illustrated in Figure 8 generally designated by the numeral 54 is in the nature of a rod having its forward portion bent to provide a U-shaped hook 55 the outer side of which is curved outwardly as indicated at 56. The inner side of the U-shaped hook is offset as indicated at 57 so that when the

board is engaged between the sides of the hook 55 it will be spaced from the shank or handle.

The tool 54 is especially adapted for use in removing the lower form boards 10 and arranging the same on the upper form board 70 for the purpose of continuing the mold.

The tool illustrated in Figure 9 and generally designated by the numeral 60 is especially adapted for use in removing the inner boards 10 and placing the same upon the upper board. The forward portion of the tool 60 is provided with a pair of spaced jaws 61 having their terminal portions extended outwardly and beveled as indicated at 62. The inner sides of the jaws 61 are provided with teeth 63 or shoulders which are engaged with the under side of the board whereby to connect the board to the tool.

Having thus described the invention, what I claim is:

1. A form comprising parallel sectional walls, tie plates extending through the walls and having rounded openings, and connecting rods extending through the plates and having flattened sides adapted to be arranged adjacent the walls whereby the rods may be released from locking engagement with the plates.

2. A form comprising a plurality of boards arranged in edge to edge relation, tie plates extending between the edges of the boards and terminating beyond the outer sides of the boards and formed with round apertures, connecting rods extended through said apertures, said rods being provided with flat sides adapted to contact with the sides of the openings adjacent the boards whereby the rods may be released from locking engagement with the wall.

3. A form comprising a plurality of boards arranged in edge to edge relation, tie plates extending between the edges of the boards and terminating beyond the outer sides of the boards and formed with apertures, connecting rods extended through said apertures, and provided with flat sides adapted to contact with the sides of the opening adjacent the boards whereby the rods may be released from locking engagement with the wall, and means to connect the ends of the boards.

4. A form comprising a plurality of boards arranged in edge to edge relation, tie plates extended between the edges of the boards and provided with rounded openings, and connecting rods extended through the rounded openings of said tie plates and having flattened sides adapted to engage the sides of the openings adjacent the boards whereby the boards may be released, the ends of said boards being provided with cleats.
